(57) **CLAIM**

The ornamental design for a balloon bracket, as shown and described.

DESCRIPTION

FIG. 1 is a front, top and right-side perspective view of a balloon bracket showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a rear, bottom and left-side perspective view thereof.

The broken lines throughout the drawing figures depict portions of the balloon bracket that form no part of the claimed design. The balloon bracket is shown with symbolic breaks in its length. The appearance of any portion of the balloon bracket between the break lines forms no part of the claimed design.
